UNITED STATES PATENT OFFICE

HERBERT J. LONG, OF NEW BRUNSWICK, NEW JERSEY

DESIGN FOR A HOT-WATER HEATER

Application filed January 22, 1930. Serial No. 34,224. Term of patent 7 years.

To all whom it may concern:

Be it known that I, HERBERT J. LONG, a hot water heater, showing my new design, citizen of the United States, residing at New Brunswick, in the county of Middlesex and State of New Jersey, have invented a new, original, and ornamental Design for Hot-Water Heater, of which the following is a specification, reference being had to the accompanying drawing, forming part thereof.

The figure is a front perspective view of a hot water heater, showing my new design, the other three sides being identical with the one shown.

I claim:

The ornamental design for a hot-water heater as shown and described.

HERBERT J. LONG.
